UNITED STATES PATENT OFFICE.

ROBERT H. BERKSTRESSER, OF YORK, PENNSYLVANIA.

LEAF-SPRING FOR VEHICLES.

1,099,533.

Specification of Letters Patent.

Patented June 9, 1914.

Application filed March 25, 1914. Serial No. 827,198.

To all whom it may concern:

Be it known that I, ROBERT H. BERKSTRESSER, a citizen of the United States, residing at York, in the county of York and State of Pennsylvania, have invented certain new and useful Improvements in Leaf-Springs for Vehicles, of which the following is a specification.

My invention relates to improvements in leaf-springs for vehicles, and has particular reference to leaf-springs having novel means for supplying a lubricant between the spring-leaves thereof.

The invention aims to provide apparatus of the above mentioned character, which is simple in construction, inexpensive to manufacture, formed of few parts, strong, and durable.

In the accompanying drawings forming a part of this specification and in which like numerals are employed to designate like parts throughout the same, Figure 1 is a side elevation of a leaf-spring embodying my invention, Fig. 2 is a central longitudinal sectional view through the same, Fig. 3 is a similar view enlarged, with parts broken away, Fig. 4 is a fragmentary bottom plan view of one of the spring-leaves, Fig. 5 is a fragmentary plan view of a spacing strip or plate, and, Fig. 6 is a central longitudinal section through the lubrication supplying binding bolt.

In the drawings, wherein for the purpose of illustration, is shown a preferred embodiment of my invention, the numeral 5 designates my improved leaf-spring, as a whole, comprising spaced superposed spring-leaves 6, 7 and 8, which are curved longitudinally in a vertical plane with their ends extending upwardly. These spring-leaves are suitably resilient and the uppermost one is provided with eyes 9, as is customary.

As more clearly shown in Fig. 4, each leaf-spring is provided upon its lower face or wall with a longitudinally extending groove 10, passing through the median line of the same and having its lower side entirely open, as shown. This lower side of the spring-leaf is further provided with short transverse grooves 11, leading into the longitudinal groove 10 and preferably angularly arranged with relation thereto, as shown.

Disposed between the spring-leaves are spacing leaves or plates 12, formed of fiber, metal, or any suitable flexible material. Each spacing leaf is provided with rela-

tively large openings 13, spaced, and arranged in longitudinal and transverse rows, as shown. The arrangement of the openings or apertures 13 and grooves 10 and 11 is such that the longitudinal groove 10 registers with the inner longitudinal row of openings 13, while the transverse grooves 11 in each transverse pair serves to connect the openings in the outer longitudinal rows with an opening in the inner longitudinal groove.

A relatively large preferably centrally arranged vertical opening 14 is formed through all of the spring-leaves and the spacing leaves to receive a combined lubrication supplying and binding vertical tubular bolt 15 as shown. This vertical tubular bolt has its lower end closed by means of a head 16, preferably fitting in a recess 17, formed in the spring-leaf 8, as shown. The vertical tubular bolt 15 is provided with spaced superposed outlet openings 16', to register with the longitudinal grooves 10, as shown. The tubular bolt 15 has its upper end exteriorly screw-threaded, as shown at 17', to receive a nut 18, as shown. A lock cap-nut 19 is preferably provided, having engagement with the screw-threads 17', and with the nut 18, to prevent its accidental rotation. This lock-cap-nut also serves to cover the open end of the tubular bolt to protect the oil or the like therein.

While I have shown one bolt 15, it is to be understood that this number may be increased, with a corresponding increasing of the number of the grooves 10.

In operation, the lubricant, such as oil, graphite, or a mixture thereof, is fed into the tubular bolt 15, by removing the lock-cap-nut. This lubricant passes by gravitation through the openings 16' into the grooves 10 and then into the grooves 11. In this manner the lubricant is supplied to the openings 13 in the spacing leaves, to thoroughly lubricate the engaging faces of the spring-leaves and spacing-leaves.

Having described my invention, I claim:

1. A leaf-spring, comprising a plurality of superposed longitudinally curved spring-leaves provided upon their lower faces with longitudinal grooves and transverse grooves leading therein, spacing-leaves arranged between the spring-leaves and provided with openings in communication with the longitudinal and transverse grooves of the spring-leaves, and a vertical tubular bolt passing through all of the spring-leaves and the

spacing-leaves to bind them together and to hold a lubricant and having outlet openings in registration with the longitudinal grooves, to supply the lubricant thereto.

2. A leaf-spring, comprising a plurality of superposed longitudinally curved spring-leaves, each of which is provided upon its lower surface with a longitudinal groove passing through the median line thereof and leading into inclined transverse spaced grooves, spacing-leaves arranged between the spring-leaves, each spacing-leaf being provided with spaced openings arranged in longitudinal and transverse rows, the longitudinal groove of the adjacent spring-leaf being in registration with the inner longitudinal row of spaced openings in the spacing-leaf and the transverse inclined grooves

serving to connect the openings in the other rows with the longitudinal groove, a vertical tubular bolt passing through the spring-leaves and the spacing-leaves to bind them together and having outlet openings to register with the longitudinal groove and its upper end exteriorly screw-threaded, a clamping nut engaging the screw-threaded end of the bolt and a lock-cap-nut engaging such screw-threaded portion to close the same and engaging the clamping nut to lock it against accidental rotation.

In testimony whereof I affix my signature in presence of two witnesses.

ROBERT H. BERKSTRESSER.
